UNITED STATES PATENT OFFICE

JOHN C. MILLER, OF CHICAGO, ILLINOIS

APPARATUS FOR CLEANING OUT CONDUITS AND THE LIKE

Application filed October 26, 1928. Serial No. 315,155.

This invention relates to apparatus for cleaning out conduits and the like, such as flues in furnaces and the water passageways in sinks, flushing bowls, and the like. It has, for one of its objects, providing a long flexible device, with some cleaning means attached to its end, arranged so that the cleaning means can be forced inwardly long distances through circuitous passageways for cleaning the passageways out or for removing obstacles from the passageways, either by forcing them inwardly or, more particularly, by attaching the device to the obstacle and pulling it outwardly.

15 A particular object of this invention is to provide means for cleaning out the passageways and, particularly, the sealing traps of flushing bowls, and for the purpose of illustrating the invention, it is shown as 20 used for that purpose. It is to be understood, however, that it may be used for various other purposes, such as those specified above.

25 Of the accompanying drawings, Fig. 1 is an elevation of a device which embodies the features of my invention, showing it applied to the cleaning of a toilet flushing bowl; Fig. 2 is an enlarged elevation of the device itself with the support rotated 90° 30 with reference to Fig. 1; Fig. 3 is a sectional view along the line 3—3 of Fig. 2; Fig. 4 is a sectional view along the line 4—4 of Fig. 3; Fig. 5 is a modification of the device of Fig. 4; Fig. 6 is a sectional view along the line 6—6 of Fig. 2; Fig. 7 35 is a modification of a portion of the feature 13 of the device; and Fig. 8 is a bottom plan view of the handle shown in Fig. 3.

40 In general, my invention comprises a long coil of wire 10, which is used for the purpose of forcing the cleaning attachment into the passageways. The attachment 11 shown is more particularly applicable to the removal of obstacles from the passageway. In 45 this case, the attachment is a coil of wire 11 which has some hooking means 12 fixed to the end; the hook itself may be attached to the end of the flexible coil 10, or it may be attached to the end of another coil 20 50 as hereinafter described.

In use, the coil 10 is adapted to be forced into circuitous passageways, such as the water passageways of the flushing bowl, with the hook 12 passing inwardly so as to catch onto any obstacle that may be in the 55 passageway, such as a rag; and to assist in this and also to assist in forcing the hook beyond obstructions, the coil is rotated. The coils 10 and 11, being composed of wire 60 spirally wound, coact with any sharp corners and screw along on the corner as rotated until the hook passes the obstruction.

In order to assist in this process, however, I provide a rounded or oval shaped device 13 which is screwed onto the end of the coil 65 10 and fastened thereon in any suitable manner. The rounded periphery of this device assists materially in passing beyond certain corners of the passageway.

To assist in rotating the coil, I provide 70 a handle 14 with a bore extending clear through into which the coil 10 passes and, by means of a thumb screw 15 or in any suitable manner, the handle may be shifted to any convenient position on the coil. It will 75 be understood that the coil may be very long and, at the same time, the handle may be shifted so as to be used in the most convenient position.

Although the coil 10 may be used as described for many purposes, yet, for other purposes, I prefer to use in conjunction with this coil an inner coil 20. The outer diameter of this coil being somewhat smaller than the bore of the main coil 10, the coil 80 85 20 may be slipped clear through the main coil with its inner end projecting out of the inner end of the main coil, and the hook 12 is fixed to the end of the inner coil.

By the use of this inner coil, the main coil 90 is strengthened without interfering materially with its flexibility, so that it may be shoved inwardly with more force and, if necessary if the main coil should refuse to move inwardly further, the inner coil may 95 be forced inwardly still further, carrying with it the attachment 12 which, preferably, is a continuation of the coil 11, and the coil 11 is preferably the inner end of the continuous coil 20. When the hook is merely 100

a part of the coil 20, it is fully as flexible as the coil. For the purpose of manipulating both of these coils, I provide a second handle 21 slidably mounted on the two coils and 5 with set screws 22 and 23 by which it can be fixed to both coils or to either one alone. By means of this handle and the set screws 22, both handles can be set on the coil 10 if desired, or, by setting both set screws 22 and 10 23, the handle 21 may be set on the two coils so as to prevent relative movement thereof, or, if desired, by loosening the set screw 22 and tightening the screw 23, the coils can be 15 rotated with reference to each other, or the inner coil may be forced inwardly or pulled outwardly with reference to the outer coil. In rotating the coils relatively, the large coil is held by the handle 24 and the small coil by the handle 21.

20 It is to be understood, however, that either of these coils may be used alone, the larger one for certain passageways, such as those of flushing bowls, and the other for other passageways, such as those of the traps of 25 washing bowls. In either case, the hook 12 or other attachments may be fixed to the inner end.

However, the cleaning device is often 30 much more effectively used when it is used in connection with the means which I have provided for holding the coil as it is being manipulated. It will be understood that, as the attachment is being worked into the passageway by the coil, the coil is rotated so 35 as to give a twisting motion to the attachment. But to manipulate the coil in this manner, I find it desirable to have some means of providing a bearing for the support and rotation of the coil.

40 When used with flushing bowls, the means which I provide for a bearing for the coil comprises a plate 25 which, preferably, is made to cover the top of the bowl 24. Also, 45 preferably, it has a lid 26 hinged to the plate 25 which can be raised as desired. For sanitary purposes, I prefer to keep the bowl entirely covered in this way. Passing through the board 25 is a tube 27 having a bend 28 on its lower end adapted to be 50 passed under the edge of the wall 30 which forms the outer end of the passageway. To protect the wall, I provide on the bend a rubber tube 31. In adjusting the apparatus to the bowl, the board is placed over the 55 bowl and the tube 27 is pushed downwardly until the end 28 is hooked onto the wall, the springs 32 (Fig. 2) yieldingly holding the tube and board snugly in position.

60 Although the plate 25 and the springs 32 will hold the device in position suitably for many purposes, yet, to hold them more rigidly, I provide a handle 35 pivoted to a clamp 36 which is adjustably mounted on the tube 27. Fixed to the handle is a cam 37 65 arranged so that when the handle is forced

downwardly the cam will pull the tube 27 upwardly with reference to the plate 25 and, thus, hold the entire outfit more rigidly in position. The clamp 36 is adjustably mounted on the tube in the following manner, although it may be adjustably mounted in other ways. Fixed on the periphery of the tube are grooves 40 and corresponding projections 41 are fixed in the bore of the clamp. Normally, the clamp will open sufficiently so that the projections will pass freely over the tube and the grooves but, as the handle 35 is passed downwardly, a projection 49 fixed to the inner arm 42 of the handle, and acting on a cam surface 43, will press the clamp arm 44 towards the arm 45 and, thus, will force the projections 41 into the corresponding recesses 40 and hold the clamp firmly in position. In order that the two cams 43 and 37 may coact properly together, I provide means for varying the length of the arm 46. Although various means may be used for this purpose, I prefer to provide a plate 47 which is pivoted at 39 between the two arms 46 and a screw 48 threaded in one arm is adapted to force the plate 47 against the other arm and hold it rigidly in any adjusted position.

50 A modification of this cam arrangement comprises a forked handle 50 which is pivoted to the arms 51 of the corresponding clamp 52 and has projections 53 on the inner end of each arm of the fork 50, which coact with cam surfaces 54 on the sides of the arms 51 which correspond to the cam surfaces 43. This arrangement may have cam arms similar to the arms 46 of the handle 35 or be otherwise arranged.

55 When thus supported, the tube 27 forms a support or bearing for the coil 10, or 20, or both, and the operator is able to force the coil downwardly through the tube 27 and the bend 28 and around through the passageways of the bowl, and he is also able to conveniently rotate the coil 10 as it is being 60 pushed down. Particularly when manipulating the two coils 10 and 20, this arrangement is desirable, as the operator is then free to give his entire attention and both hands to manipulating the coils and, particularly, in operating the coils relative to each other.

65 To adapt the apparatus to various devices, for instance, to flushing bowls of different shapes, I prefer to mount the tube 27 rotatably in the plate 25. It is sometimes desirable to have the hook 28 of the tube relative to the plate, as shown in Fig. 1, or rotated through 90°, as shown in Fig. 2, or rotated through 180°, or otherwise. As arranged, the tube 27 can be freely rotated with reference to the plate by loosening the set screw 60. For the purpose of holding the various members substantially in position, and for other reasons, I provide a coil 70

spring 61 mounted on the tube between the collar 33 and the plate, or, preferably, between the collar and a plate 62 mounted on the under side of the plate 25.

5 It is also desirable to slidably mount the tube 27 in the plate 25 and, for this purpose, I provide a slot 65 in the plate 25 and also in the plate 62 if desired. In this manner, the tube may be shifted in the plate 10 25 to conform with the particular position of the wall 30 or for other reasons. To facilitate this, I mount the upper ends of the 15 springs 32 on slidably mounted rods 66. In this manner, as the tube 27 is shifted with reference to the plate 25, the supports of the upper ends of the springs are shifted accordingly and no inconvenience results.

It will be understood that other modifications could be made in the details of the apparatus which I have illustrated and described herein by those skilled in the art without departing from the spirit of my invention as disclosed by the following claims. For instance, the device 13 may be replaced 25 by a device 70 which may be composed of independent wire and in any manner fastened onto the inner end of the tube 10. I prefer, however, to form this bulge 70 by winding back on itself the wires of the coil 30 10, so that it will be rigidly and conveniently fixed to the coil 10. It will be understood that, by removing the handles from the coils, one or both of them may be slipped from the tube 27 and the coils may then 35 be used independent of the supporting apparatus or, if desired, the coils may be reversed so that the normal outer ends may be used inwardly; and any suitable attachments may be connected therewith, such as 40 the cork-screw coil 71.

The coils 10 and 20 may be made of any suitable material. I prefer, however, for the purpose to make them of music or piano wire. While I do not wish to be limited to 45 the dimensions specified, yet, I prefer to make the outer coil with an outer diameter of substantially $7/16''$ and out of piano wire having a diameter of about $.118''$, and the inner coil with an outer diameter of 50 about $3/6''$ and from piano wire of substantially $.071''$ in diameter.

When the coils are made of suitable piano wire, they are very flexible but strong and not easily bent. For instance, the hook 12 55 on the end of the coil 20 can be pulled through the coil 10 and also through either handle without being permanently bent.

I claim:

60 1. A passageway cleaner comprising a long flexible coil of spring wire, a cleaning attachment fixed to one end of the coil, a handle slidably mounted on the coil, the adjacent turns of the coil being substantially in contact, and a collar mounted on the attachment end of said coil with the attach-

ment projecting, the periphery of said collar being oval-shaped.

2. A passageway cleaner as claimed in claim 1, in which said collar comprises a coil of wire with its outer end fixed to said first mentioned coil.

3. A passageway cleaner comprising a long flexible coil of spring wire, a handle slidably mounted on the coil, the adjacent turns of the coil being substantially in contact, a collar mounted on the attachment end of said coil, the periphery of said collar being oval-shaped, and a second elongated coil, said second coil being longer than and slidably mounted in said first mentioned coil, and a cleaning attachment fixed to one end of said second coil.

4. A passageway cleaner support comprising a tube adapted to receive in its bore a flexible rod or coil, a plate having an opening therethrough in which said tube is mounted, said plate being adapted to be placed against a member fixed with reference to said passageway, said tube having means on its inner end for attaching to a member fixed with reference to said passageway, and means for pressing said plate towards said inner end relative to said tube.

5. A passageway cleaner support as claimed in claim 4, in which said means comprises a handle fixed to said tube outside of said plate and cam means adapted to press against said plate as the handle is operated.

6. A passageway cleaner support as claimed in claim 4, in which said means comprises a handle slidably mounted on said tube and means adapted to hold said handle rigidly relative to said tube as said handle is operated, and other means tending to press said plate towards said inner tube end as said handle is operated.

7. A passageway cleaner support as claimed in claim 4, and also comprising yielding means for holding said tube against movement inwardly in said board, said tube and yielding means being slidably mounted with reference to said plate.

In testimony whereof, I hereunto set my hand.

JOHN C. MILLER.
